ASSIGNORS TO AMERICAN GASACCUMULATOR COMPANY, OF ELIZABETH, NEW
JERSEY, A CORPORATION OF NEW JERSEY.

FLASH-LIGHT APPARATUS.

Application filed October 17, 1923. Serial No. 669,185.

To all whom it may concern:

Be it known that we, ELOF H. MEDÉN and CARL LINDAHL, respectively a subject of the King of Sweden and a citizen of the United States, and residents of Short Hills, in the county of Union, State of New Jersey, and Hillside, in the county of Union, State of New Jersey, have invented an Improvement in Flash-Light Apparatus, of which the following is a specification.

Our invention relates to improvements in apparatus of the character or type wherein a pivoted valve lever is actuated to open and close a valve or valves and in which the actuating means generally comprises a flexible diaphragm which is directly or indirectly connected to the said valve lever and in which the diaphragm is actuated by a gas or liquid under pressure.

One object of the invention is to provide an improvement in means for adjusting and controlling the stroke of the flexible diaphragm which improvement is of general application to flashlight apparatus of the character or type indicated.

Another object of the invention is to provide a flashlight apparatus (in which the outlet opening only is adapted to be opened and closed by an oscillatory valve member) with means for controlling the extent of the stroke of said valve member and for magnetically tending to hold the said member either in closed or open position whereby a more efficient closing and opening thereof is effected.

In flashlight apparatus of the type or character under consideration the stroke of the flexible diaphragm is practically proportional to the amount of gas used and as the quantity of gas is generally very small the means for adjusting the stroke should be sensitive and free from any binding action so as to allow the diaphragm to assume its natural position without exerting eccentric forces upon the regulating means. This is of importance because the normal forces acting upon the diaphragm are generally extremely small. A further object of the invention, therefore, is to provide means whereby the liability of any binding action between the diaphragm and the means for adjusting the stroke thereof is eliminated.

In flashlight apparatus in which only the

outlet for the gas is controlled by a valve the magnetic means as heretofore constructed and arranged for insuring a quick or sudden opening or closing of the valve has been unsatisfactory because the magnetic forces have been active for closing the valve only when the same was either in closed position or very nearly closed and practically of no effect when the valve was in fully opened position.

In the constructions of this character the valves have been moved toward the valve seat slowly under the influence of the flexible diaphragm as it collapsed during the passage of gas from the casing through the valve controlled outlet provided for that purpose. In moving from its open to its closed position the valve would become gradually subjected to the action of magnetic forces so that the force with which the valve has been caused to contact with its seat has not been sufficient to insure at all times a tight closing of the valve which has constituted one objectionable feature present in the constructions of the prior art. In the present construction embodying our invention magnetic forces operate to hold the opening and closing valve in both its open and closed positions. Upon the escape of gas or other fluid from the casing the flexible diaphragm as it collapses under the influence of a spring tends to cause closing movement of the valve but such movement is resisted by the holding action of the magnetic forces. As a result of this resistance a certain amount of force is accumulated within the spring until it is finally sufficient to overcome the magnetic attraction in consequence of which the valve is released suddenly with a snap toward the valve seat and is immediately brought under the influence of magnetic forces tending to attract it to the valve seat and the action of these forces combined with the accumulated force of the diaphragm or rather of the spring pressing against the same operates to cause the valve to strike its seat with a blow of considerable force whereby any dust which may be present is displaced and the valve closely and hermetically sealed. The arrangement of means for effecting this result insures a fixed and constant stroke of the valve lever which is a very desirable feature of construction.

Other objects and advantages in addition to those above enumerated will be pointed out in the detailed description of our invention or will be apparent from such description.

In order that the invention may be readily understood and its practical advantages fully appreciated reference should be had to the accompanying drawing in which one form of mechanical embodiment thereof is shown. However, it will be understood that the invention is susceptible of embodiment in other forms of construction than that shown and that changes in the details thereof may be made within the scope of the claims without departing from the invention.

In the drawings:

Fig. 1 is a central vertical sectional view of a flashlight apparatus embodying our invention;

Fig. 2 is a transverse sectional view taken on the line 2—2 of Fig. 1;

Fig. 3 is a similar view taken on the line 3—3 of Fig. 1;

Fig. 4 is a view taken on the line 4—4 of Fig. 1; and

Fig. 5 is a vertical transverse sectional view taken on the line 5—5 of Fig. 1.

Referring to the drawings: 1 designates a casing closed at one end by a flexible diaphragm 2 in the usual and well known manner. The gas is adapted to enter the casing through an inlet 3 and to escape therefrom through an outlet 4 which is controlled by a valve structure comprising a valve body or seat 5 and an oscillatable valve lever 6. The said lever 6 is fulcrumed at one end a distance from the valve seat upon pins 7 secured to the top of the casing 1. The said lever is held against these fulcrum pins by means of a pin 8 which engages the underside of the lever 6 at a point intermediate the pins 7, as shown in Fig. 3 of the drawing. The pin 8 is supported upon a slightly bowed plate spring 9 secured at its opposite ends to the sides of the casing 1, as is indicated in Fig. 3. The valve lever 6 is so supported upon and by the fulcrum pins that it is free to oscillate between the valve body or seat 5 and an adjustable screw 10 which is secured to one of the legs (the lower leg) of a U-shaped steel member 11.

A steel plate 12 is secured to the underside of the top of the casing 1 at one end by means of the screw-threaded stems 12' of the fulcrum pins 7 by means of which the latter are secured to the top of said casing and at its opposite end by means of the valve body or seat 5, the screw-threaded upper portion of which extends through an opening through the said plate. The upper portion of the said valve seat also passes through an opening through the upper leg of the U-shaped steel member 11 so that

said leg is clamped firmly against the underside of the adjacent end portion of the plate 12 while the latter is clamped against the top of the casing 1. The opposite end of said plate 12 is likewise clamped firmly between the base portions of the fulcrum pins 7 and the opposing underside portion of the top of the casing 1.

In the construction embodying our invention either the steel plate 12 or the valve lever 6, which also is of steel, is permanently magnetized. Generally the steel valve lever 6 will be permanently magnetized in which case the plate 12, the valve body 5, the member 11 and the adjustable screw 10 will constitute the armature therefor. In such event the magnetic flux, when the valve is in closed position as shown in Fig. 1 of the drawing, will pass through the parts 6, 7, 12, 5 and back to 6 and when the valve is in open position the said magnetic flux will pass through 6, 7, 12, 11, 10 and back to 6. In case the plate 12, instead of the valve lever 6, should be permanently magnetized it will be apparent that both the valve body 5 and the screw 10 will have the same polarity and the lever 6 in such case would constitute the armature. The effect and operation will be the same whether the plate 12 is permanently magnetized or whether the valve lever 6 is permanently magnetized.

The variation in the lengths of the periods during which gas escapes from the flasher casing depends upon the stroke of the flexible diaphragm. For the purpose of regulating such stroke a lever 13 is pivotally connected intermediate its ends at the point 14 to the oscillatable valve lever 6, at a point relatively near its outer or oscillating end. The inner portion of the said lever 13 to the left of its pivot point 14 (having reference to Fig. 1 of the drawing) is, in the construction shown, shorter than the opposite or outer end portion thereof. The inner upper end of the lever is rounded and pointed, as indicated at 15, in order that when it contacts with the flat under side of the top of the eyelet or bail 16 which is secured to the central portion of the diaphragm 2 it will adjust itself thereto so that there will be no tendency of a binding action between the two contacting portions. The outer end of the lever 13 is adapted to contact with the lower end of an adjustable screw 17 which constitutes a stop to limit the pivotal movement thereof upon its pivot at 14 as the diaphragm 2 expands. The screw 17 projects exteriorly of the casing to facilitate adjustment thereof. The position of the inner end of the adjustable screw 17 regulates or controls the extent of outward movement of the diaphragm 2 (under the influence of the fluid within the casing) before the valve lever 6 is opened and its position likewise controls

- the extent of inward movement of the diaphragm 2 before the said valve is closed. If the adjustable stop 17 should be adjusted outwardly thereby permitting greater outward movement of the diaphragm 2 before the opening of the valve 6 is effected it follows that there must be a correspondingly greater movement of the diaphragm in the opposite direction before the valve is closed.
- 5 A spring 18 presses against the outer side of the central portion of the diaphragm 2 and tends to press or force the same inwardly.
- 10 The speed of entry of the gas through the inlet 3 into the casing 1 may be controlled by a needle valve 20 which is adjustable from the exterior of the said casing as is apparent. The period during which the valve lever 6 will remain in closed position 15 will depend upon the rate at which the fluid is admitted into the chamber 1 and also upon the position of the inner or lower end of the adjustable screw 17.
- 15 When the valve lever 6 is in open position with its outer or oscillatable end in contact with the inner end of the adjustable screw 20 the gas or other fluid escapes from the casing through the opening through the valve body 5 and the outlet 4. The spring 25 18 presses against the outer side of the flexible diaphragm 2 or a part connected therewith and tends to cause inward movement thereof and as the gas or other fluid escapes from the chamber of the casing 1 the top 30 of the eyelet or bail member 16 contacts with the lever 6 and tends to disengage it from the adjustable screw 10. Such disengagement, however, is not effected until the gas or other fluid escapes sufficiently 35 from the chamber of said casing to permit the pressure or force exerted by the spring 18 to overcome the force of magnetic attraction between the said lever 6 and the screw 10. When, however, the gas or other fluid 40 has escaped to a sufficient extent to permit the force or pressure of the spring 18 to cause separation of the lever 6 from the screw 10 such separation is effected with a snap, the said diaphragm being snapped forward under the influence of the stored up pressure or force of the spring 18 to cause a corresponding quick movement of the lever 6 away from the screw 10 toward its seat upon the valve body 5.
- 45 As the valve lever moves toward its valve seat its motion is accelerated by the force of the magnetic attraction exerted by the valve lever body thereon. The said valve strikes the valve seat with considerable force so 50 that it is firmly and closely seated against the same to hermetically seal the opening therethrough. At the moment of closure of the valve opening by the valve lever 6 the eyelet or bail member 16 may contact with 55 said lever. At such time the point 15 of the inner end of the lever 13 would be in contact with the flat underside of the top of the eyelet 16 while the opposite end thereof will be spaced from the lower end of the stop 17. As the gas or other fluid enters the chamber 70 of the casing 1 the flexible diaphragm is moved outwardly, the eyelet or bail member 16 moving therewith away from the lever 6. Such outward movement, however, has no effect upon the valve lever 6 until after the 75 outer end of the lever 13 contacts with the lower end of the stop 17. The expansive force of the gas or other fluid within the chamber is not sufficient at the moment that the outer end of the lever 13 contacts with 80 the screw 17 to effect separation of the lever 6 from its valve seat with the result that the expansive force of the gas is accumulated so that finally when the valve lever 6 is separated or disconnected from the valve body 85 5 such separation is effected with a snap or quickly. Outward or opening movement of the lever is limited by the stop 10 which may be adjusted to vary the extent or amplitude of the oscillatory movements of the said 90 valve lever 6.
- 95 It will be seen that by our invention we have provided a flashlight apparatus with extremely efficient opening and closing means.
- Having thus described our invention, what we claim and desire to secure by Letters Patent is:
1. In a flashlight apparatus, the combination of a valve lever pivoted at one end, a valve body having an opening adapted to be closed by the said lever, means for limiting the opening movement of said lever, means whereby magnetic forces tend to hold the said valve lever in its closed or in its open 100 position according as it is in the one or the other position, and means for controlling the periods of the closed and open positions of said valve lever which means comprises a pivoted lever and an adjustable stop member which cooperates therewith.
  2. In a flashlight apparatus, the combination of a valve lever pivoted at one end, means for actuating said lever to open and close the same, a valve body having an opening adapted to be closed by the said lever, means for limiting the opening movement of said lever, means whereby magnetic forces tend to hold the said valve lever in its closed or in its open position according 115 as it is in the one or the other position, and means comprising an adjustable stop device interposed between said lever and its actuating means for controlling the periods of the closed and open positions of said valve lever.
  3. In a flashlight apparatus, the combination of a casing one end of which is closed by a movable diaphragm, a valve lever situated within said casing and pivoted at one 130

end, a valve body having an opening which is adapted to be opened and closed by the oscillating end portion of the said valve lever, a stop for limiting the opening movements of the said valve lever, means whereby magnetic forces acting upon the oscillatable end portion of the said valve lever tend to hold the same either in its closed or open position against forces tending to open or close the same, and means comprising an adjustable stop device for controlling the movements of said valve lever with respect to the movements of said diaphragm.

4. In a flashlight apparatus, the combination of a magnetized valve lever pivotally supported at one end the other end thereof being oscillatable, a valve body having an opening therethrough which is adapted to be closed and opened by the oscillating end portion of the said lever, an adjustable stop for limiting the opening movements of the said valve lever, and means associated with the said valve lever comprising a pivoted lever and a stop device cooperating therewith for regulating and controlling the frequency of the oscillations of the said valve lever.

5. In a flashlight apparatus, the combination of a casing provided with a movable diaphragm for closing one end thereof, a magnetized valve lever pivotally supported at one end the other end thereof being oscillatable, a valve body having an outlet opening therethrough which is adapted to be closed and opened by the oscillating end portion of the said lever, an adjustable stop for limiting the opening movements of the said lever, and means interposed between the said lever and the said diaphragm for regulating and controlling the frequency of the oscillations of the said valve lever which means comprises a pivoted lever carried by said valve lever.

6. In a flashlight apparatus, the combination of a valve casing, one end of which is closed by a flexible diaphragm and which casing is provided with inlet and outlet openings through which a fluid under pressure is adapted to enter and leave the said casing, a valve lever pivoted at one end, the opposite end of which is adapted to close and open the said outlet opening, means interposed between the said lever and the said diaphragm for controlling the frequency of the opening and closing movements of the said lever which means comprises a pivoted lever and an adjustable stop device co-operating therewith, and means whereby the said valve lever is adapted to strike with a blow to close the said outlet opening.

7. In a flashlight apparatus, the combination of a casing, one end of which is closed by a flexible diaphragm and which casing is provided with inlet and outlet openings through which a fluid under pres-

sure is adapted to enter and leave the said casing, a valve lever pivoted at one end, the opposite end of which is adapted to close and open the said outlet opening, means whereby the said valve lever is adapted to be actuated by movements of the said diaphragm to effect closing and opening movements of the said lever, and adjustable means for limiting the outward movement of the said diaphragm under the influence of the pressure of the fluid in said casing.

8. In a flashlight apparatus, the combination of a casing, one end of which is closed by a flexible diaphragm and which casing is provided with inlet and outlet openings through which a fluid under pressure enters and leaves the said casing, an oscillatable valve member which is adapted to close and open the said outlet opening, an adjustable stop, and means having connection with the said valve member and interposed between the said stop and the said diaphragm whereby the amplitude of the movements of the said diaphragm may be regulated and controlled.

9. In a flashlight apparatus, the combination of a casing, one end of which is closed by a vibratory flexible diaphragm and which casing is provided with inlet and outlet openings through which a fluid under pressure enters and leaves the said casing, an oscillatable valve member which is adapted to close and open the outlet opening, an adjustable stop, a lever pivoted intermediate its ends to the said valve member, one end of which lever co-operates with the said diaphragm structure and is actuated thereby and the other of which is adapted to contact with the said adjustable stop.

10. In a flashlight apparatus, the combination of a casing, one end of which is closed by a flexible diaphragm and which casing is provided with inlet and outlet openings through which a fluid under pressure is adapted to enter and leave the said casing, an oscillatable valve member which is adapted to close and open the said outlet opening, an adjustable stop projecting into the said valve casing, a lever pivoted intermediate its ends to the said oscillatable valve member and the said pivot being nearer to one end of said lever than to the other end thereof, the outer end of the longer end portion being adapted to contact with the said stop and the opposite shorter end portion co-operating with the said flexible diaphragm and being actuated thereby.

11. In a flashlight apparatus, the combination of a casing, one end of which is closed by a flexible diaphragm and which casing is provided with inlet and outlet openings through which a fluid under pressure is adapted to enter and leave the said casing, a valve lever pivotally supported at one end and the opposite end of which is adapted to

close and open the said outlet opening, a stop for limiting the opening movements of the said valve lever, connections between the said flexible diaphragm and the said valve lever, said connections being located between said stop and the pivotal point of said lever and means which co-acts with a member of said connections for regulating and controlling the movement of the opening of the said valve lever with respect to the position of the said diaphragm.

12. In a flashlight apparatus, a casing, one end of which is closed by a flexible diaphragm and which casing is provided with inlet and outlet openings through which a fluid is adapted to enter and leave the said casing, a valve lever fulcrumed at one end and the opposite end of which is adapted to close and open the outlet opening, and means interposed between the said valve lever and the said diaphragm whereby movements of the latter effect opening and closing of the said valve which means comprises a lever fulcrumed upon the said valve lever.

13. In a flashlight apparatus, a casing, one end of which is closed by a flexible diaphragm and which casing is provided with inlet and outlet openings through which a fluid is adapted to enter and leave the said casing, a fulcrumed valve lever, and adjustable means interposed between said lever and the said diaphragm for opening and closing the said valve, said adjustable means comprising a stop which is adjustable and which projects into the said casing from the outside of the same, and a lever pivotally supported upon the said valve lever, one end of which lever is in co-operative relation to the said diaphragm and adapted to be actuated thereby while the other end thereof is adapted to contact with said stop.

14. In a flashlight apparatus, a casing, one end of which is closed by a flexible diaphragm and which casing is provided with inlet and outlet openings through which a fluid under pressure is adapted to enter and leave the said casing, a valve lever for alternately opening and closing said opening, means whereby the said valve lever is positioned in both its closed and open positions in a magnetic circuit, and means interposed between the said valve lever and the said diaphragm for opening and closing the said valve lever which last means comprises a lever fulcrumed upon the said valve lever.

15. In a flashlight apparatus, the combination of a casing, one end of which is closed by a flexible diaphragm and which casing is provided with inlet and outlet openings through which fluid under pressure is adapted to enter and leave the said casing, a fulcrumed valve lever, means whereby the said valve lever is situated in a magnetic circuit in both its closed and open positions, an adjustable means interposed between said valve lever and said diaphragm whereby movements of the latter effect closing and opening movement of the said valve lever, said adjustable means comprising an adjustable stop which extends into the said casing, and a lever fulcrumed upon the said valve lever, one end of which lever is in co-operative relation to the said diaphragm and adapted to be actuated thereby while the other end thereof is adapted to contact with said stop.

In testimony that we claim the foregoing as our invention, we have hereunto signed our names this 11th day of October, A. D. 1923.

ELOF H. MEDÉN.
CARL LINDAHL.
